(57) **CLAIM**

The ornamental design for a socket holder rail, as shown and described.

DESCRIPTION

FIG. 1 is a perspective view of a socket holder rail, showing my new design;

FIG. 2 is another perspective view of the socket holder rail depicted in FIG. 1;

FIG. 3 is a front elevation view of the socket holder rail depicted in FIG. 1;

FIG. 4 is a rear elevation view of the socket holder rail depicted in FIG. 1;

FIG. 5 is a left side elevation view of the socket holder rail depicted in FIG. 1;

FIG. 6 is a right side elevation view of the socket holder rail depicted in FIG. 1;

FIG. 7 is a top plan view of the socket holder rail depicted in FIG. 1; and,

FIG. 8 is a bottom plan view of the socket holder rail depicted in FIG. 1.

The broken lines in the drawings depict portions of the socket holder rail that form no part of the claimed design.
